UNITED STATES PATENT OFFICE.

HARRY R. LANGSLOW, OF ROCHESTER, NEW YORK.

SCHOOL-CHAIR.

1,217,783.

Specification of Letters Patent. Patented Feb. 27, 1917.

Application filed February 17, 1915. Serial No. 8,707.

To all whom it may concern:

Be it known that I, HARRY R. LANGSLOW, of Rochester, in the county of Monroe and State of New York, have invented certain new and useful Improvements in School-Chairs; and I do hereby declare the following to be a full, clear, and exact description of the same, reference being had to the accompanying drawings, forming a part of this specification, and to the reference-numerals marked thereon.

My invention has for its object to improve the construction of school chairs, and more generally the class of chairs embodying a desk portion in conjunction therewith, for supporting a book or other article. More particularly the invention has for its purpose to provide a desk portion or arm that is removable from its operative position and adapted to be conveniently held beneath the seat of the chair when not in use, in such a manner as to permit of its ready removal and at the same time present a neat and slight appearance. To these and other ends the invention consists in certain improvements and combinations of parts, all as will be hereinafter more fully described, the novel features being pointed out in the claim at the end of the specification.

In the drawings:

Figure 1 is a side elevation showing a chair equipped with a preferred embodiment of the invention;

Fig. 2 is a front elevation of the same with the desk portion in full lines beneath the seat of the chair, and in dotted lines in its operative position;

Fig. 3 is a vertical sectional view with the desk portion beneath the seat;

Fig. 4 is a sectional view on the line 4^a—4^a of Fig. 1;

Fig. 5 is an enlarged sectional view on the line 5^a—5^a of Fig. 1, and

Fig. 6 is a detail view.

Similar reference characters throughout the several views indicate the same parts.

The chair of the present embodiment comprises a frame including a back portion 1, legs 2 and a seat portion 3.

Arranged on the frame, and preferably attached to one of the side pieces 4 is a tapered socket which is constructed of sheet metal and comprises an inner plate 5 and an outer plate 6, the latter having flanges 7 which are engaged by the overlapping portions 8 of the inner plate. The outer plate is bowed

inwardly at 9 thereby forming a pair of tapered recesses 10, the sides 11 of the outer plate converging from top to bottom as shown in Fig. 1.

The desk portion or arm includes a table 12 which lies normally in a substantially horizontal position, when in its operative position as shown in Fig. 1. The table 12 carries a standard or leg 13 preferably formed of sheet metal and including a tapered end portion 14 which engages the socket on the frame and includes a pair of hollow ribs or enlargements 15 which engage the tapered recesses 10 of the socket. This construction affords an extremely efficient arrangement that enables the desk portion to be held quite rigidly. 16 is a sheet metal brace arranged between the standard 13 and the table 12.

When the desk portion is not in use, it is desirable to remove it and preferably to house it beneath the chair so that it will be readily accessible and at the same time not in the way. To this end I provide a recess in the frame of the chair beneath the seat, and preferably formed at the front. The recess in the present structure is formed by the front legs, and cross pieces 17 and 18, the former being arranged adjacent to the bottom of the chair seat, while the latter is secured between the legs and includes an upwardly projecting flange 19. Retaining means are provided to hold the desk portion and to this end a lug 20 is attached to the chair seat and arranged to engage the front of the table of the desk portion when the latter is positioned as shown in Fig. 3, while 21 is a movable catch which also engages the front of the table 12 when positioned as shown in Figs. 2 and 3.

When the catch 21 is turned a quarter of a turn, it releases the desk portion which can then be removed and positioned in the socket for use. The desk portion may be held beneath the seat by retaining means other than the recess and co-

operating fastening devices which have been described, the chief purpose of the improvement being to provide for housing the desk portion beneath the seat so that it will not interfere in any way with the ordinary use of the chair when the desk portion is not being utilized.

The construction described can be economically manufactured, and is characterized by comparatively great strength and rigidity, all of which is an essential and most desirable feature in connection with chairs of this

type which are subjected to such constant and rough usage, and must stand long continued and hard strains without impairing their efficiency and usefulness. Another important advantage of the invention is that it affords practically two chairs in one, which is susceptible of use either for study, writing, or for rest, or other purposes.

I claim as my invention:
10 The combination with the frame of a chair, of a sheet metal socket embodying a

pair of tapered recesses, a removable desk portion, and a standard on the desk portion including a pair of tapered hollow ribs having engagement with the aforesaid recesses 15 and formed by bending a piece of sheet metal upon itself at its edges.

HARRY R. LANGSLOW.
